UNITED STATES PATENT OFFICE

ARTHUR W. SIEVERS, OF VALPARAISO, INDIANA, ASSIGNOR TO NOAH S. AMSTUTZ

SPELLEr SIGN

Original application filed January 24, 1924, Serial No. 688,315. Divided and this application filed November 15, 1928. Serial No. 319,533.

My invention relates to improvements in speller signs and it more especially consists of the features hereinafter pointed out in the claims.

The purpose of my invention is to produce a simplified advertising sign that will spell words, sentences, etc., letter by letter or word by word; that is entirely automatic in its operation; that is susceptible of enlargement or expansion; that is portable; that makes a minimum demand for electric current; and that on account of its extraordinary simplicity avoids the use of a driving motor, connecting gears, levers, etc.

15 This is divisional application of Serial No. 688,315 filed January 24, 1924.

With these and other ends in view, I illustrate in the accompanying drawing such instances of adaptation as will disclose the broad underlying features without limiting myself to the specific details shown thereon and described herein.

20 Figure 1 is a side elevation of a revolving illuminator combined with an individual letter cabinet.

Fig. 2 is a plan view of Fig. 1 showing a plurality of letter cabinets.

Fig. 3 is a front elevation of a letter cabinet having a curved face.

30 Fig. 4 is a front elevation of a letter cabinet having a straight sign portion.

Fig. 5 is an enlarged plan view partly in section of the tangential letter cabinet shown in the lower half of Fig. 2.

35 In practically carrying out my invention I may use any desired type of incandescent lamp 1 mounted on a suitable receptacle 2 which is secured to a base 3. An outlet 4 serves for the cord which supplies the electricity for the lamp, and a control switch, not shown, may be connected to this cord. A wire 5 or other support is secured to the base 3 by means of the foot 6. This wire is bent at its upper end so as to terminate in a point 7 above the lamp 1. This point 7 serves to support the propeller 9 which at its center is provided with a hollow glass or other suitable bearing 8. Outside of the blades of the propeller 9 an annular rim may be formed on 50 which the cylinder 10 is supported.

The lamp 1, base 3, support 5, propeller 9, and a cylinder 10 open at the bottom, constitute all the required elements for producing an automatic self-acting rotating illuminator. The cylinder 10 may have a single letter 55 slit 11 or an entire word opening 12, shown in Fig. 2.

The heat developed by the lamp 1 rises upward through the open bottom of the cylinder 10 and in passing by the blades of the fan causes it to revolve. In so doing it successively brings the narrow slit 11 in line with each letter of one of the letter cabinets 16, and the wide opening 12 in the cylinder 10 is also successively brought in line with the entire 60 small end of an individual letter cabinet, as shown in Fig. 2.

The device shown on the drawing comprises a suitable base 14 which has an arc 17 formed at one end in order to fit against the base 3. From each end of the arc 17, radial edges 18 are formed ninety degrees from each other so as to permit a grouping of four individual bases, if desired, around a single rotating cylinder 10. On the base 14 standards or supports 15 are placed. These hold the letter compartment casing 16 which is provided with radial partitions 19 that are held in place by a bottom or floor 13 and a top cover 20. The inner or small end of the 70 cabinet terminates in close proximity to the cylinder 10, and the outer face of the cabinet is closed by a translucent or transparent member 21 on which the individual letters are formed, as shown in Figs. 3 and 4. Such 75 letters on the screen 21, in connection with it form variable light transmitting areas. Two forms of casing 16 are shown in Fig. 2. The one to the right of the lamp terminates in the arc of a circle while the one shown below the lamp terminates in a straight line. Any 80 number of partitions 19 may be used within the angular range of an observer's vision as may be desired, and in order to make the spelling visible within the entire circumference of the cylinder 10 the four casings may be duplicates of each other.

With the individual letter cabinets shown, the successive spelling of a word is also due to the movement of the narrow slit 11 formed 85 90 95 100

in the cylinder 10. One or more of these slits may be formed and they may be combined with a single wide opening 12 which will successively illuminate letter by letter, and 5 at one time illuminate all the letters simultaneously. It is apparent that by confining the luminosity between the partition walls 19, the transition from letter to letter will be more pronounced and in addition a greater 10 length of space is thereby secured so that more letters can be used for a given advertisement.

It is of course obvious that I may almost unlimitedly change the expedients I have illustrated and described without departing 15 from the spirit of my invention.

What I claim is:

1. In automatic moving signs, a rotatable cylinder, means for automatically moving the cylinder, stationary means adjacent the cylinder wall containing variable light transmitting areas in plural units constituting separate groups, and means carried by the cylinder to successively in recurring periods illuminate the units of one group and also simultaneously illuminate another group of such units periodically.
2. In automatic moving signs, a rotatable cylinder, means for automatically moving the cylinder, separate groups of separate stationary means positioned adjacent different portions of the cylinder wall containing separate light transmitting areas in plural units, and means carried by the cylinder to successively in recurring periods illuminate the units of one group one by one and also simultaneously illuminate a single group of other units periodically.
3. In automatic moving signs, a rotatable cylinder, means for setting the cylinder in motion, one or more stationary diverging letter cabinets constituting separate groups positioned with the small end of the cabinet adjacent the rotating cylinder, a series of radial partitions in the cabinet, a translucent covering for the large end of the cabinet, different letters or symbols formed on the covering in line with the spaces between the partitions, and means on the cylinder adapted to successively project luminosity between the partitions one by one and also in sequence therewith simultaneously illuminate all of the spaces between partitions of a separate group.

In testimony whereof I affix my signature.
ARTHUR W. SIEVERS.
